(57) **CLAIM**

The ornamental design for a vehicle wheel with a bear logo, as shown and described.

DESCRIPTION

FIG. 1 is a perspective view of a vehicle wheel with a bear logo, of the new design;

FIG. 2 is a side elevation view thereof;

FIG. 3 is a top plan view thereof;

FIG. 4 is a rear elevation view thereof;

FIG. 5 is a bottom plan view thereof;

FIG. 6 is a front elevation view thereof;

FIG. 7 is a back side elevation view thereof, opposite that of FIG. 2; and,

FIG. 8 is an enlarged elevation view of FIG. 2.

The dashed-dashed broken lines showing portions of the vehicle wheel with a bear logo form no part of the claimed design. The dashed-dot-dashed broken lines depict boundary lines that form no part of the claimed design.
